(57) **CLAIM**

The ornamental design for a wallpaper hanging tool, as shown.

DESCRIPTION

FIG. 1 is a front perspective view of a wallpaper hanging tool, showing the new design;

FIG. 2 is a bottom perspective view of the present design;

FIG. 3 is a front elevation view of the present design;

FIG. 4 is a left-side elevation view of the present design;

FIG. 5 is a rear elevation view of the present design;

FIG. 6 is a right-side elevation view of the present design;

FIG. 7 is a top view of the present design; and,

FIG. 8 is a bottom view of the present design.

The broken lines depict portions of the wallpaper hanging tool that form no part of the claimed design.
